RIBBON SPOOL ASSEMBLY FOR TYPEWRITER OR LIKE MACHINES

Harry L. Lambert, West Hartford, Conn., assignor to
Royal McBee Corporation, New York, N. Y., a cor-
poration of New York

Application January 11, 1955, Serial No. 481,081

14 Claims. (Cl. 197—175)

This invention relates to ribbon spool assemblies for typewriter or like machines, and more particularly to an improved and efficient construction of mechanism including a spool carried element adapted to respond to unwinding of ribbon from the spool for operating a ribbon reversing mechanism.

An object of the invention is to provide an improved construction of the kind referred to which is simple and constituted by a minimum number of parts.

Another object of the invention is to provide a construction of the character stated including a leaf spring of novel and improved formation for cooperating with the spool carried responsive element for urging it to one of its positions.

A further object of the invention is to provide a construction including a leaf spring formed integrally with or as part of a spool flange, and which nevertheless is soft and resilient enough in its action and certain in its operation to insure that the spool mounted responsive element will be moved to its operating position for cooperation with the ribbon reversing mechanism when the ribbon has been unwound without, however, endangering the positioning of the responsive element for non-engagement with the ribbon reversing mechanism when a ribbon is wound upon the spool.

Other objects of the invention will become apparent from a reading of the following description, the appended claims, and the accompanying drawings, in which:

Figure 1 is an elevational view of a ribbon spool embodying the invention, showing one end portion of a typewriter ribbon attached thereto;

Figure 2 is an elevational view showing right and left-hand ribbon spools of a typewriting machine, a typewriter ribbon being indicated in dot-dash-lines, and immediately associated typewriter parts being shown fragmentarily in section and in elevation, this view being on a reduced scale as compared to Figure 1;

Figure 3 is a bottom plan view of the spool and ribbon shown in Figure 1;

Figure 4 is a fragmentary elevational view of part of the spool shown in Figures 1 and 3, drawn on an enlarged scale, and showing a trigger for operating a ribbon reversing mechanism in its operated or active position; and

Figure 5 is a view similar to Figure 4 but showing the trigger in its normal or idle position.

The drawings show two typewriter ribbon spools S, S, typewriter frame parts F, F, and two ribbon spool shafts or spindles 1, 1. The shafts 1, 1 are shown as being equipped with toothed or notched discs 2, 2 adapted to be operatively connected to parts on the ribbon spools S, S in the usual manner so that the spools may be driven by the shafts 1, 1 selectively, according to which of the shafts is driven by the typewriter mechanism. That is, a selected one of the shafts 1 is driven by the typewriter mechanism to wind ribbon upon the associated spool while the other shaft 1 is free to turn to permit ribbon to be unwound from the spool mounted on the freely

2

rotatable shaft. Also shown are parts 3, 3 included in the ribbon reversing mechanism which may be of known form, and which therefore is not illustrated completely.

The spools S, S may be of identical construction. Each 5 spool S includes spaced upper and lower flanges 4 and 5 joined together in spaced relationship by arms extending from one flange to the other. In the form shown, three arms 6, 7 and 8 integral with the upper flange 4 are struck out from this flange and are bent downwardly. The lower ends of the arms 6, 7 and 8 have narrow parts extending through openings in the lower flange 5 and providing shoulders adapted to abut against the top of the lower flange 5. One such shoulder 7a is shown in each of Figures 4 and 5. The arms 6 and 10 7 are provided with similar shoulders not designated by reference characters in the drawing.

The narrow lower end parts of the arms 6, 7 and 8 which extend through registering openings in the lower flange 5 are formed with bifurcations 6b, 7b and 8b, respectively, which project beyond or below the bottom flange 5. The two bifurcations of each pair of bifurcations are bent oppositely to one another for securing the associated arm to the bottom flange 5. In this way, the arms 6, 7 and 8 secure the flanges 4 and 5 in spaced assembled relationship. The spool may be stiffened or braced by an arm 9 which is struck out of the top flange 4 and bent downwardly to abut the bottom flange 5.

The bottom flange 5 is formed with a central opening 10 adapted to receive a reduced part 11 of the associated shaft or spindle 1; and the top flange 4 is depressed or cupped and apertured to form a bearing part 12 which receives the upper end of the reduced shaft part 11. In this way, the spool may readily be mounted upon and removed from the associated shaft. Two ears 13, 13 struck out of the bottom flange 5 and bent downwardly are adapted to enter the notches or tooth interspaces in the disc 2 on the associated shaft so as to cause the spool to be rotated when the shaft is driven.

The ribbon may be attached to the spool in any suitable manner, for example in either of the two ways disclosed in the patent to Hart, 2,486,473, granted November 1, 1949. According to the more conventional method of attachment of the ribbon, an end portion thereof is impaled upon one of a pair of prongs 6 formed 40 on the arm 6. In a preferred method of attaching the ribbon end to the spool, a looped ribbon end R^a is moved downwardly through an opening or cut-out 14 in the spool top flange 4 and is positioned over an anchoring post 15 which is struck out from the bottom flange 5 and bent upwardly so that its free upper end is positioned below the cut-out 14 and is thus unobstructed for permitting the ribbon looped end R^a easily to be slipped over the anchoring post 15. The cut-out 14 may conveniently be formed where the arm 9 is bent out of the flange 4 and extended downwardly to abut the bottom flange 5. The spool hub structure is constituted by the arms connecting the flanges 4 and 5.

It is usual for typewriter or like machines to include 50 mechanism responsive to unwinding of the ribbon completely or substantially completely from one of the ribbon spools for reversing the ribbon spool driving mechanism for causing the substantially exhausted spool to begin to function as a wind-up spool and to feed the ribbon in the opposite direction. The present invention provides an improved construction of and mounting for a trigger element T which responds to unwinding of the ribbon substantially completely from the spool for operating a control part of the ribbon drive reversing mechanism, such as one of the parts shown at 3 in Figure 2. The trigger element T is formed from a piece of sheet metal bent and twisted so as to include a ribbon engaging finger 16 extending alongside the hub structure, an actuating finger

17 extending at an angle to the finger 16 and exteriorly of the ribbon spool, and a shaft 18 between the fingers 16 and 17 and having its ends mounted in bearing openings 19 formed in ears 20 struck out from the bottom flange 5 and bent downwardly. The trigger T is mounted for rocking from a normal position, in which the ribbon engaging finger 16 is engaged and held by the ribbon and the actuating finger 17 is in an idle position as shown in Figure 5 in which it cannot engage the reversing mechanism part 3, to an operated position as shown in Figure 4 in which the ribbon engaging finger 16 is released by unwinding of the ribbon and the actuating finger 17 is in its operating position in which it is disposed to engage the ribbon reversing mechanism control part 3.

An improved structure is provided for yieldably urging the trigger element T toward its operative position as shown in Figure 4. In the form shown, the shaft 18 is formed with flat parts 18^a, one of which is acted upon by a leaf spring 21 in a manner tending to rock the element T counterclockwise from the position shown in Figure 5 to the operated position shown in Figure 4. The leaf spring 21 is generally of J shape and preferably is formed integrally with the spool bottom flange 5. As clearly shown in Figures 3, 4 and 5, the spring 21 is struck out from the spool flange 5 and has one of its ends integrally united at 21^a with the flange 5, one portion 21^b of the spring extending circumferentially of the spool flange 5 adjacent to its periphery and merging with a return-curve part 21^c from which extends a free end part 21^d. The spring free end part 21^d presses against a pressure responsive part 18^b on the trigger T for tending to rock the trigger from its normal position shown in Figure 5 to its operative position shown in Figure 4. The pressure responsive part 18^b is eccentric to the axis of the shaft 18 and is constituted by the upper left-hand edge of the flat part 18^a as shown in Figures 4 and 5.

When a spool is in normal use and is functioning as the supply spool from which ribbon is being drawn to be fed along the typing line of the typewriter or other machine, the parts will be in the positions shown in Figure 5. The spring 21 will be pressing against the pressure responsive eccentric edge part 18^b of the trigger shaft 18 so as to tend to rock the trigger counterclockwise to its Figure 4 position. However, as long as ribbon wound on the spool hub structure is in engagement with the ribbon engaging finger 16, the holding action of the ribbon itself will maintain the trigger in its normal position so that the actuating finger 17 will be in its raised position and will be incapable of engaging the ribbon reversing control part 3. When the ribbon has been nearly exhausted from the spool, or drawn therefrom to the extent that the ribbon no longer engages the trigger finger 16, the trigger is rendered free to be rocked from its operated position by the force exerted by the leaf spring 21 on the flat part 18^a of the shaft 18, and more particularly on the pressure responsive edge 18^c. The spring force will then rock the trigger T to the operated position shown in Figure 4 in which the trigger finger 17 will be sufficiently low to engage the ribbon reversing control part 3 for operating the latter and the associated reversing mechanism, not shown, thereby to cause the spool from which ribbon was exhausted to be driven in the opposite direction and thus to become a take-up spool for drawing ribbon from the other spool.

The J-shaped leaf spring 21 is so formed and located that its longer leg extends generally circumferentially with respect to the spool, and its shorter leg extends generally reversely to the longer leg 21^b and over the flat part 18^a of the trigger shaft 18. By virtue of this arrangement, a soft and very resilient spring of considerable extent is provided economically from the metal of the spool structure itself and is capable of providing the required light but nevertheless certain bias on the trigger T.

The construction shown embodies the invention in a preferred form, but it is intended that the disclosure be

illustrative rather than definitive, the invention being defined in the appended claims.

I claim:

- 5 1. In a typewriter or like machine ribbon spool assembly, a spool comprising a flange and a hub structure; a trigger comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 10 2. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 15 3. In a typewriter or like machine ribbon spool assembly, a spool comprising a flange and a hub structure; a trigger comprising a ribbon engageable finger, an actuating finger and a shaft having a substantially flat portion; means on said spool engaging said shaft and mounting said trigger with said ribbon engaging finger extending alongside said hub structure and said actuating finger projecting exteriorly of said flange, said mounting means enabling said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 20 4. In a typewriter or like machine ribbon spool assembly, a spool comprising a flange and a hub structure; a trigger formed of a single piece of sheet metal and comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 25 5. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 30 6. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 35 7. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 40 8. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 45 9. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 50 10. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 55 11. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 60 12. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 65 13. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 70 14. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.
- 75 15. In a typewriter or like machine ribbon spool assembly, a spool comprising a flange and a hub structure; a trigger comprising a ribbon engageable finger, an actuating finger and a shaft between said fingers and having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end part fixed with respect to said spool and another part engaging the substantially flat portion of said shaft for yieldably urging said trigger to its operated position.

ating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring formed integrally with a part of said spool and having a part engaging the substantially flat portion of said shaft for yieldably urging said trigger to its operated position.

6. In a typewriter or like machine ribbon spool assembly, a spool comprising a sheet metal flange and a hub structure; a trigger comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring struck out of said flange and having one end part integral with said flange and another part engaging the substantially flat portion of said shaft for yieldably urging said trigger to its operated position.

7. In a typewriter or like machine ribbon spool assembly, a spool comprising a flange and a hub structure; a trigger comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end fixed with respect to said flange adjacent the periphery thereof, a first portion extending generally circumferentially of said flange, a return-curve portion, and a free end portion extending generally reversely to said first portion and engaging the substantially flat portion of said shaft for yieldably urging said trigger to its operated position.

8. In a typewriter or like machine ribbon spool assembly, a spool comprising a flange and a hub structure; a trigger comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring generally of J shape having the end of its longer leg fixed with respect to said flange and having its shorter leg engaging the substantially flat portion of said shaft for yieldably urging said trigger to its operated position.

9. In a typewriter or like machine ribbon spool assembly, a spool comprising a sheet metal flange and a hub structure; a trigger comprising a ribbon engageable finger, an actuating finger and a shaft having a substantially flat portion; means on said spool engaging said shaft and mounting said trigger to rock from a normal position in which said ribbon engageable finger is disposed to be engaged and held by ribbon wound on said hub structure

and said actuating finger is disposed in idle position to an operated position in which said ribbon engageable finger is released by unwinding of the ribbon from said hub structure and said actuating finger is disposed in operative position; and a leaf spring generally of J shape struck out of said flange, the end of the longer leg of said spring being integrally united to said flange and said longer leg extending circumferentially with respect to said flange, and the shorter leg of said spring extending generally reversely to said longer leg and engaging the substantially flat portion of said shaft for yieldably urging said trigger to its operated position.

10. In a typewriter or like machine ribbon spool assembly, a spool comprising a sheet metal flange and a hub structure; a trigger having a ribbon engageable finger, an actuating finger, a shaft between said fingers, and a pressure responsive part eccentric to the shaft axis; means engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring struck out of said flange and having one end part integral with said flange and another part pressing against said pressure responsive part for yieldably urging said trigger to its operated position.

11. In a typewriter or like machine ribbon spool assembly, a spool comprising a flange and a hub structure; a trigger having a ribbon engageable finger, an actuating finger, a shaft between said fingers, and a pressure responsive part eccentric to the shaft axis; means engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring having one end fixed with respect to said flange adjacent the periphery thereof, a first portion extending generally circumferentially of said flange, a return-curve portion, and a free end portion extending generally reversely to said first portion and bearing on said pressure responsive part for yieldably urging said trigger to its operated position.

12. In a typewriter or like machine ribbon spool assembly, a spool comprising a flange and a hub structure; a trigger having a ribbon engageable finger, an actuating finger, a shaft between said fingers, and a pressure responsive part eccentric to the shaft axis; means engaging said shaft and mounting said trigger to rock from a normal position in which said ribbon engageable finger is disposed to be engaged and held by ribbon wound on said hub structure and said actuating finger is disposed in idle position to an operated position in which said ribbon engageable finger is released by unwinding of the ribbon from said hub structure and said actuating finger is disposed in operative position; and a leaf spring generally of J shape having the end of its longer leg fixed with respect to said flange and having its shorter leg pressing against said pressure responsive part for yieldably urging said trigger to its operated position.

13. In a typewriter or like machine ribbon spool assembly, a spool comprising a sheet metal flange and a hub structure; a trigger having a ribbon engageable finger, an actuating finger, a shaft between said fingers, and a pressure responsive part eccentric to the shaft axis; means engaging said shaft and mounting said trigger to rock from a normal position in which said ribbon engageable finger is disposed to be engaged and held by

ribbon wound on said hub structure and said actuating finger is disposed in idle position to an operated position in which said ribbon engageable finger is released by unwinding of the ribbon from said hub structure and said actuating finger is disposed in operative position; and a leaf spring generally of J shape struck out of said flange, the end of the longer leg of said spring being integrally united to said flange and said longer leg extending circumferentially of said flange and inside the periphery thereof, and the shorter leg of said spring extending generally reversely to said longer leg and pressing against said pressure responsive part for yieldably urging said trigger to its operated position.

14. In a typewriter or like machine ribbon spool assembly, two spaced flanges, one of which is formed with a plurality of openings; and a hub structure constituted

5 by a plurality of arms formed integrally with the other of said flanges and having bifurcated end portions respectively projecting through and beyond said openings, the parts of said bifurcations of at least certain of said end

10 portions which project beyond the associated openings in said one of said flanges respectively being bent oppositely for securing said arms to said one of said flanges.
